COMBINED AUTOMOBILE GRILLE BAR AND PARKING LAMP HOUSING

Virgil M. Exner, Birmingham, Mich., assignor to Chrysler Corporation, Highland Park, Mich., a corporation of Delaware

Application May 12, 1953, Serial No. 24,966

Term of patent 7 years

(Cl. D14—18)

To all whom it may concern:

Be it known that I, Virgil M. Exner, a citizen of the United States, residing in the city of Birmingham, county of Oakland, and State of Michigan, have invented a new, original, and ornamental Design for a Combined Automobile Grille Bar and Parking Lamp Housing, of which the following is a specification, reference being had to the accompanying drawings, forming part thereof, in which:

Fig. 1 is a front elevation of a combined automobile grille bar and parking lamp housing, showing my new design;

Fig. 2 is a fragmentary front elevation of a portion of a combined automobile grille bar and parking lamp housing on an enlarged scale, showing my novel design;

Fig. 3 is a fragmentary top plan view of a portion of the combined automobile grille bar and parking lamp housing;

Fig. 4 is an end elevation of the combined automobile grille bar and parking lamp housing;

Figs. 5, 6, 7, 8 and 9 are sectional views taken on the lines 5—5, 6—6, 7—7, 8—8 and 9—9 respectively of Fig. 2; and

Fig. 10 is a perspective view of the combined automobile grille bar and parking lamp housing wherein the broken lines indicating a portion of an automobile are for illustrative purposes only.

I claim:

The ornamental design for a combined automobile grille bar and parking lamp housing, substantially as shown and described.
